UNITED STATES PATENT OFFICE.

SAMUEL POOLE, OF BROOKLYN, N. Y., ASSIGNOR TO ELIZA W. POOLE, OF SAME PLACE, AND THOMAS L. BULLOCK, OF NEW YORK, N. Y.

TONGS FOR PICKLES, FRUITS, &c.

SPECIFICATION forming part of Letters Patent No. 294,147, dated February 26, 1884.

Application filed January 7, 1884. (No model.)

To all whom it may concern:

Be it known that I, SAMUEL POOLE, of Brooklyn, in the county of Kings and State of New York, have invented a new and useful Improvement in Tongs for Pickles, Fruits, &c.; and the following is declared to be a description of the same.

Tongs and forks have heretofore been used for removing pickles, fruits, &c., from cans and jars, and also for handling lump-sugar.

The object of my invention is to simplify and improve the devices for the aforesaid purpose.

My invention consists of a pair of pointed 15 toggle-claws mounted upon a standard and moved by a push-rod and head operated by hand, and I use a spiral spring to force the toggle-claws together and produce a pressure or force sufficient to grasp and hold a pickle 20 or other article while it is being removed from a jar or other vessel to a plate or other receptacle.

My improved tongs are available for pickles, 25 cucumbers, or oysters, for canned fruits and meats, for lump-sugar, and for other edible articles where tongs or forks are now employed.

In the drawings, Figure 1 is an elevation of the tongs closed and section of the handle. Fig. 2 is an elevation of the tongs with the 30 toggle-claws open. Fig. 3 is a plan of the same, and Fig. 4 is an edge view of toggle-arms.

The handle portion of my improved tongs is made of four pieces—viz., the disk *a* and 35 tube *b*; the tubular stem *c* and head *d*. The disk *a* and tube *b* are in one piece or attached together, and the stem *c* is screwed or soldered into the tube *b* at one end and fastened to the head *d* at the other end. The push-rod *e* and 40 push-button *f* for moving the toggle-arms *h h'* operate through the tube *b*, stem *c*, and head *d*, and one end of the rod *e* is connected to the block *g*. This block *g* is slotted (see Fig. 3) and provided with the pins 1 2. The toggle-claws *h h'* are preferably made of the shape 45 shown, and they are pivoted to the head *d* by pins 3 4, and are made with slotted jaws *i i'*,

entering the slots in the block *g*. The pins 1 2, entering the slots in the jaws *i i'*, serve as a means for moving them open or shut. There 50 is a spiral spring, *k*, in the tube *b* around the push-rod *e*, and said spring has a bearing at one end against the push-button *f* and at the other end against the end of the stem *c*, and the expansive action of said spring against 55 these parts keeps the toggle-claws closed when not in use, and pressed tightly against the article between their ends when in use.

To operate my improved tongs, the instrument is taken between the fingers, with the 60 disk *a* against the index and second finger, the thumb resting against the push-button *f*. Pressure on the push-button *f* moves the rod *e* endwise, compressing the spiral spring *k* and causing the block *g* to open the toggle-claws. 65 Upon relieving the push-button *f* the expansion of the spiral spring closes the toggle-claws toward each other to grasp any intervening article or material.

I do not limit myself to the size or design 70 of the tongs, nor to the particular construction of the toggle-claws nor the number or shape of the claw-points, for these may be varied according to the uses to which said tongs are to be put.

I am aware that a fork has been made in 75 which the prongs are pivoted to a rod and provided with links connecting their rear ends to a tube, a spring being provided to close the prongs.

I claim as my invention—
In combination with a tubular stem, push-rod, head, and spring, the claws pivoted at 3 4 upon the head *d*, and provided with short slotted arms extending toward each other, a 85 block upon the push-rod, and pins passing through the slotted arms, substantially as set forth.

Signed by me this 4th day of January, A. D. 1884.

SAMUEL POOLE.
